UNITED STATES PATENT OFFICE.

WILLIAM M. TRAINOR, OF NEW YORK, N. Y.

GARMENT.

1,120,985.

Specification of Letters Patent. Patented Dec. 15, 1914.

Application filed March 24, 1914. Serial No. 826,846.

To all whom it may concern:

Be it known that I, WILLIAM M. TRAINOR, a citizen of the United States, residing in the city, county, and State of New York, 5 have invented a new and useful Improvement in Garments, of which the following is a specification.

My invention relates to an improved garment in which the lower, or trouser portion, 10 is made of a piece of material folded on itself to form the body and leg portions and my objects are the production of such garments in a cheap, economical manner in which there will be a minimum of waste and 15 labor and which will result in a shapely, well fitting garment.

In the drawing, which shows the invention applied to a children's romper, Figure 1 is a perspective view of the garment and 20 Fig. 2 a view of the trousers part before making up.

The waist portion 1 is of any suitable pattern and may be made separate from or integral with the trousers portion or the trousers 25 portion may be made alone for use as underwear or the like.

My invention relates to the trousers portion and in making the same a piece of material is laid out as shown in Fig. 2 with 30 the body portions *a* and *b* having the sides bowed as shown at 4, 4' and 5, 5'. The leg

openings 2 and 3 are cut out in line with the narrow portion and are spaced from the edges and from one another. These leg openings 2 and 3 may be Shirred with elastic 35 if desired. The parts *a* and *b* are then folded together with the leg openings 2 and 3 at the fold and the bowed sides sewed together as shown in Fig. 1 making the full fashioned 40 trousers with the crotch portion 6.

This garment may be made of any desired material and of one or more pieces and is particularly adapted to children's rompers and garments and may also be used in connection with the production of under- 45 wear and the like.

I claim:

A garment having a waist and leg portions composed of material folded on itself with leg openings at the fold spaced from 50 one another and located at a substantial distance from the side edges, the sides being permanently united whereby trousers are formed.

In testimony whereof I have hereunto set 55 my hand this 21st day of March, 1914, in the presence of two attesting witnesses.

WILLIAM M. TRAINOR.

Witnesses:
